PITLESS WELL UNIT HOUSING FOR USE WITH SUBMERSIBLE PUMPS

Homer L. Andrew, Superior, Wis., assignor to Duplex
Manufacturing Company, Superior, Wis., a corpora-
tion of Wisconsin

Filed July 1, 1965, Ser. No. 85,990

Term of patent 14 years

(Cl. D65—1)

FIG. 1

FIG. 3

FIG. 2

FIG. 1 is a front perspective view of a pitless well unit housing for use with submersible pumps showing my new design.

FIG. 2 is a top plan view thereof; and

FIG. 3 is a rear perspective view.

I claim:

The ornamental design for a pitless well unit housing for use with submersible pumps, substantially as shown.
